MECHANISM FOR DRIVING THE IMPELLER
OF A SUPERCHARGER FOR AN INTERNAL
COMBUSTION ENGINE

Frank Bernard Halford, London, England

Application March 11, 1933, Serial No. 660,424
In Great Britain March 12, 1932

20 Claims. (Cl. 74—410)

This invention relates to mechanism for driving the impeller of a supercharger for an internal combustion engine and has for its object to effect modifications in transmission mechanism of the type commonly employed for this purpose in order to obviate certain disadvantages present in this known mechanism.

A construction of this transmission mechanism as commonly employed comprises a driving shaft 10 and a driven shaft mounted coaxially, the latter carrying the impeller. On the driving shaft is mounted a gear wheel and a pinion is similarly mounted on the driven shaft. These wheels mesh respectively with pinions and gear wheels 15 carried on two or more lay shafts. A slipping clutch is disposed on each lay shaft, parts of the clutch being respectively connected to the toothed wheels on that shaft. In this construction equalization of the torque through the lay 20 shafts is effected by slip in the clutches but it is difficult to construct clutches with such similar limiting torque capacities under all conditions as will ensure the desired equalization of the torque through the lay shafts.

25 The improved construction comprises as in the known arrangement a driving shaft, a driven shaft which carries or is coupled to the impeller and may be coaxial with the driving shaft, and one or more pairs of lay shafts with gearing 30 through which the drive is transmitted from the driving shaft through the lay shafts to the driven impeller device, and according to this invention there is included in this gearing balancing or differential mechanism, one element of which is 35 connected directly or through transmission gearing to the driving or driven shaft, while the other elements are connected directly or through transmission mechanism respectively to the two lay shafts so as to ensure equalization of torque 40 transmitted through such lay shafts.

In one arrangement according to the invention the transmission mechanism between the driving or the driven shaft and the lay shafts comprises at least one pair of twin coaxial gear 45 wheels mounted coaxially with respect to either the driving or the driven shaft, these wheels meshing respectively with toothed wheels on corresponding lay shafts, and balancing or differential mechanism through which the drive is 50 transmitted between the twin coaxial gear wheels and the driving or driven shaft, this balancing or differential mechanism constituting such a connection between the twin coaxial gear wheels that its reaction on one gear wheel is dependent 55 upon there being equal reaction on the other

gear wheel so that at least some degree of relative rotation between the pair of gear wheels can take place and equalization of the torque through the lay shafts is ensured.

For example, a pair of twin gear wheels may 60 be freely mounted coaxially with the driving shaft, each of these gear wheels meshing with a pinion on a separate lay shaft and also constituting one member of a differential gear, for example of conventional type, whose planet 65 wheels are disposed on a carrier member constituting a driving member mounted on and driven by the driving shaft. The drive is thus transmitted from the driving shaft to both twin 70 wheels through the planet pinions of the differential gear while this gear permits relative rotation of the twin wheels and ensures equalization of torque in the two lay shafts.

In an alternative arrangement the main driving shaft may transmit power through gearing 75 to a subsidiary or intermediate driving shaft on which is mounted the driving element of differential or balancing gearing, the two driven elements of which are mounted to rotate freely coaxially with the subsidiary driving shaft. One 80 of these driven elements constitutes a lay shaft and is connected by gearing to the driven shaft which is preferably coaxial with the main driving shaft, while the other element is connected by gearing, including for example a gear wheel 85 coaxial with the main driving shaft, to a second lay shaft also connected by gearing to the driven shaft.

In a still further arrangement similar in other respects to the above, the two driven elements 90 of the differential mechanism may respectively be connected through gearing to two separate lay shafts through which power is transmitted to the driven shaft.

In either of the above arrangements, in place 95 of a differential gear of conventional type the balancing mechanism may comprise a rotatable member, hereinafter referred to as a driving member, carrying radial bearing members on each of which is freely mounted a two-armed lever one arm of which is connected to one driven element arranged to rotate coaxially with the driving member, while the other arm engages the other driven element also arranged coaxially 100 with the driving member, the arrangement constituting in effect differential mechanism but being such, by reason of the connection of the two-armed levers respectively to the two driven elements, that only limited relative rotation between the two driven members can take place. 110

Again, in some cases the balancing mechanism may comprise a driving member connected to the driven members by springs, spring-actuated or other movable or yielding members constituting a yielding connection between the driving member and each of the driven members which will ensure substantial equalization of torque through the two lay shafts to the driven shaft.

In constructions according to the present invention, one or more slipping clutch devices, for example of the friction or hydraulic type, may be provided either in the mechanism for transmitting power to the differential or balancing mechanism or between the driven shaft and the impeller for the purpose of limiting the torque which can be transmitted through the mechanism and preventing excessive stresses, for example when the driving shaft accelerates or decelerates rapidly. Again, where differential mechanism of conventional type is employed permitting free relative rotation to any required extent between the three elements of the differential mechanism, one or more slipping clutch devices, for example of the friction or hydraulic type, may be arranged so that the slip therein results in relative rotation between the parts of the differential mechanism.

The invention may be carried into practice in various ways but a number of constructions according to the present invention are illustrated somewhat diagrammatically by way of example in the accompanying drawings, in which

Figure 1 is a side elevation partly in section of one construction employing a direct drive without the interposition of friction or other slipping clutches between the driving and driven shafts.

Figure 2 is a similar view to Figure 1 of an alternative construction incorporating clutches of the slipping friction type.

Figure 3 is a similar view to Figure 1 showing an alternative construction employing a hydraulic transmission device of the reaction type through which the drive is transmitted from one of the lay shafts to the driven shaft.

Figure 4 is a similar view to Figure 1 of a still further arrangement employing a slipping clutch between the driving shaft and a driving member.

Figure 5 is a similar view to Figure 1 of a still further arrangement employing a hydraulic transmission device of the reaction type between the driven shaft and the impeller of the supercharger, and

Figure 6 shows a still further arrangement employing a friction clutch in the transmission mechanism.

In the construction shown in Figure 1 the apparatus comprises a driving shaft A mounted in fixed bearings A¹ and arranged coaxially with a driven shaft B mounted in fixed bearings B¹ and carrying an impeller B². Mounted to rotate freely coaxially with the driving shaft are twin gear wheels C, C¹. The gear wheel C meshes with a gear wheel D on a lay shaft D¹ mounted in fixed bearings D² and carrying a gear wheel D³ which meshes with a gear wheel B³ on the driven shaft B while the gear wheel C¹ meshes with a gear wheel E on a lay shaft E¹ mounted in fixed bearings E² and carrying a gear wheel E³ meshing with the gear wheel B³ on the driven shaft B, the axes of the two lay shafts D¹ and E¹ lying on diametrically opposite sides of the common axis of the driving and driven shafts A and B and the gear wheels D and E being of the same diameter as are also the gear wheels D³

and E³. Mounted on the driving shaft A is a driving member F in the form of a carrier having supported therein two radial shafts F¹ on each of which is rotatably mounted a coupling member F² having two arms the ends of which are provided with spherical or like bearing members F³ engaging corresponding sockets in the two gear wheels C and C¹.

It will thus be seen that power is transmitted from the driving shaft A through the carrier F and the members F² to the two gear wheels C and C¹ so as to cause these to rotate substantially in unison whereby power is transmitted through the two lay shafts D¹ and E¹ to the driven shaft B. At the same time by reason of the ability of the members F² to rock about their pivot pins F¹ slight relative rotational movement can take place between the two gear wheels C and C¹ so that the two gear wheels C and C¹ and the members F, F¹, F² may be regarded as constituting differential mechanism permitting only limited relative movement between the parts thereof which, however, is sufficient to ensure that substantially the same torque shall be transmitted respectively through the two lay shafts D¹ and E¹ so that this torque and the forces applied to the driven shaft by the gear wheels D³ and E³ are substantially balanced.

In the alternative construction illustrated in Figure 2 the general arrangement is similar to that shown in Figure 1 and comprises a driving shaft A mounted in fixed bearings A¹ and arranged coaxially with a driven shaft B mounted in fixed bearings B¹ and carrying an impeller B². The driving shaft A has mounted to rotate freely coaxially therewith two gear wheels G, G¹. The gear wheel G meshes with a gear wheel H on a lay shaft H¹, while the gear wheel G¹ meshes with a gear wheel J on a lay shaft J¹. The lay shaft H has freely mounted thereon a gear wheel H² which is connected to the lay shaft through a friction clutch device H³, the driving member H⁴ of which is secured to the lay shaft while the driven member is constituted by a sleeve H⁵ rigidly connected to the gear wheel. Similarly the lay shaft J¹ has freely mounted thereon a gear wheel J² which is connected to the lay shaft by a friction clutch device J³. The gear wheels H² and J² both mesh with a gear wheel B³ on the driven shaft B.

Formed on the adjacent inner faces of the two gear wheels G and G¹ are teeth constituting bevel wheels which mesh with bevel wheels K freely mounted on radial shafts K¹ supported by a carrier K² rigidly connected to the driving shaft A, this mechanism constituting a differential gear whereby power can be transmitted from the driving shaft A to the two gear wheels G, G¹. It will be seen that with this arrangement torque is transmitted from the driving shaft A equally to the two lay shafts H¹, J¹ through the differential gear irrespective of differences in slip which may take place in the two clutches J³ and H³. Moreover these clutches act to prevent excessive torque being transmitted through the mechanism as a whole.

In the arrangement shown in Figure 3 the construction and arrangement of the driving shaft A and driven shaft B, the twin gear wheels G, G¹ and the differential mechanism is substantially the same as that shown in Figure 2. In this construction, however, the lay shaft J¹ has a gear wheel J⁴ rigidly mounted thereon and meshing with the gear wheel B³, whereas the lay shaft H¹ has mounted thereon one part H⁶

of a hydraulic transmission device of the reaction type, the other part H^7 of which is rigidly connected to a gear wheel H^8 meshing with the gear wheel B^3 .

5 In this construction it will be seen that power is transmitted from the driving shaft A through the differential mechanism K , K^1 , K^2 to the two gear wheels G , G^1 and thence to the two lay shafts H^1 , J^1 so that substantially the same torque is transmitted to each lay shaft. Relative rotation between the two parts of the hydraulic transmission device H^6 , H^7 can, however, take place by reason of relative rotation which can take place between the two gear wheels G , G^1 . Thus during acceleration of the driving shaft the rotational speed of the shaft H^1 may exceed considerably that of the shaft J^1 .

10 Moreover when the driving shaft is accelerated rapidly so that slip tends to take place in the hydraulic clutch device the differential mechanism acts as multiplying gearing to increase the speed of the member H^6 and due to this effect the hydraulic clutch can be of smaller size than would be the case if the speed of its driving member was always proportional to the speed of the driving shaft.

15 In the arrangement shown in Figure 4 the apparatus comprises a driving shaft A mounted in bearings A^1 and a coaxial driven shaft B mounted in fixed bearings B^1 and carrying an impeller B^2 , the shaft B carrying a gear wheel B^3 which meshes with gear wheels L and M respectively on lay shafts L^1 and M^1 mounted in fixed bearings L^2 and M^2 and carrying also gear wheels L^3 and M^3 . Power is transmitted to the gear wheels L^3 and M^3 by twin gear wheels N, N^1 mounted to rotate freely coaxially with the driving shaft A and having bevel wheels formed on their adjacent faces and meshing with cooperating bevel wheels N^2 rotatably mounted on radial pivot pins N^3 supported by a carrier N^4 which is rigidly connected to a sleeve O. It will thus be seen that power can be transmitted from the sleeve O through the differential mechanism N^2 , N^3 , N^4 equally to the twin gear wheels N, N^1 and thence through the two lay shafts L^1 , M^1 to the driven shaft B. Power is transmitted from the driving shaft A to the sleeve O through a slipping clutch device P of the friction type, the driving member P^1 of which is rigidly connected to the driving shaft while the sleeve O constitutes the driven member. With this arrangement it will be seen that the friction clutch device P limits the torque which can be transmitted through the mechanism as a whole.

20 In the construction shown in Figure 5 the arrangement is generally similar to that shown in Figure 4 except that instead of the member N^4 being mounted on a sleeve O and connected to the driving shaft by a friction clutch device, the carrier N^4 is directly mounted on the driving shaft A while, instead of the driven shaft B being directly connected to the impeller, the gear wheel B^3 which meshes with the two gear wheels L and M is rigidly connected to one part Q of a hydraulic transmission device of the reaction type, the other part Q^1 of which is rigidly connected to the driven shaft B carrying the impeller B^2 . With this arrangement the hydraulic transmission device Q, Q^1 by reason of the relative rotation which can take place between its parts limits the torque which can be transmitted through the apparatus as a whole while the differential mechanism ensures equalization of torque in the two lay shafts.

25 In the construction shown in Figure 6 the apparatus comprises a main driving shaft R having rigidly mounted thereon a gear wheel R^1 which meshes with a gear wheel S on a subsidiary driving shaft S^1 mounted in fixed bearings S^2 . Mounted on the subsidiary driving shaft S^1 is differential mechanism comprising a driving element formed integral with or rigidly connected to the shaft S^1 and having radial bearing members S^3 carrying bevel wheels S^4 , and two driven elements in the form of bevel wheels T and U meshing with the bevel wheels S^4 . The gear wheel T is rigidly connected to a gear wheel T^1 which meshes with a gear wheel V on the driven shaft V^1 carrying the impeller V^2 of a supercharger. The gear wheel U is rigidly connected to a gear wheel U^1 which meshes with a gear wheel W freely mounted coaxially with the main driving shaft R and in turn meshing with a gear wheel X on a lay shaft X^1 . The lay shaft X^1 is connected through a friction clutch device X^2 to a gear wheel X^3 also meshing with the gear wheel V on the driven shaft V^1 .

30 The arrangement is such that the transmission ratio as between the gear wheel U^1 and the gear wheel X is a 1:1 ratio, the two gear wheels X and T^1 being of the same diameter.

35 In this construction it will be seen that the drive is transmitted from the main driving shaft R to the subsidiary driving shaft S^1 and thence a balanced drive is transmitted through the differential mechanism respectively on the one hand direct to the gear wheel T^1 and on the other hand through the gearing U, U^1 , W, X and the clutch X^2 to the gear wheel X^3 , so that there is substantial equalization of the torque transmitted respectively through the hollow lay shaft constituted by the gear wheels T and T^1 and their connecting sleeve and the lay shaft X^1 to the driven shaft B.

40 In an alternative construction otherwise generally similar to that shown in Figure 6, the gear wheel T^1 instead of meshing directly with the gear wheel on the driven shaft, may be of the same diameter as the gear wheel U^1 and may mesh with a gear wheel on a second lay shaft which in turn carries a gear wheel meshing with the gear wheel on the driven shaft at a point diametrically opposite to the gear wheel X^3 .

45 What I claim as my invention and desire to secure by Letters Patent is:—

1. Mechanism for driving the impeller of a supercharger for an internal combustion engine, including in combination a main driving shaft, a driven shaft, an impeller coupled to the driven shaft, an intermediate driving shaft arranged with its axis parallel to that of the main driving shaft, gearing connecting the intermediate driving shaft to the main driving shaft, differential balancing mechanism arranged coaxially with the intermediate driving shaft and comprising a driving member connected to the intermediate driving shaft and two driven members freely rotatable about the axis of the intermediate driving shaft, a gear wheel rigidly connected to one of such driven elements, a gear wheel on the driven shaft with which such driven element gear wheel meshes, a lay shaft, a gear wheel on said lay shaft meshing with the gear wheel on the driven shaft, and gearing connecting the other driven element of the differential mechanism to the lay shaft, the arrangement being such that transmission ratio of 1:1 exists as between the lay shaft and its associated driven element.

2. Mechanism for driving the impeller of a supercharger for an internal combustion engine including in combination a driving shaft, a driven shaft, an impeller connected to the driven shaft, at least two lay shafts, gearing connecting each lay shaft to the driving and to the driven shaft, the gearing between the lay shafts and one of such driving and driven shafts including mechanical differential mechanism ensuring equalization of torque through the lay shafts, and a slipping clutch device included in the mechanism to prevent transmission of excessive torque therethrough. 80
3. Mechanism for driving the impeller of a supercharger for an internal combustion engine including in combination a driving shaft, a driven shaft, an impeller connected to the driven shaft, at least two lay shafts, gearing connecting each lay shaft to the driving and to the driven shaft, the gearing between the lay shaft and one of such driving and driven shafts including mechanical differential mechanism one element of which is rigidly connected to the said second coaxial shaft while the other two elements are each freely mounted coaxially with the said second coaxial shaft and are connected by gearing respectively to the two lay shafts, and a slipping clutch device of the hydraulic reaction type for transmitting power between driving and driven parts of one of the lay shafts. 85
4. Mechanism for driving the impeller of a supercharger for an internal combustion engine including in combination a main driving shaft, a driven shaft coaxial therewith, an impeller carried by the driven shaft, an intermediate driving shaft arranged parallel to the main driving shaft, gearing connecting the main driving shaft to the intermediate driving shaft, mechanical differential transmission mechanism arranged coaxially with the intermediate driving shaft and comprising a driving element connected to the intermediate driving shaft, and two driven elements arranged coaxially with this intermediate driving shaft, a gear wheel on the driven shaft, driving gear wheels meshing with diametrically opposite parts of the gear wheel on the driven shaft, means for transmitting power from one driven element of the differential mechanism to one of such driving gear wheels and from the other driven element of the differential mechanism to the other driving gear wheel, the arrangement being such that the transmission ratio as between each of the driven elements of the differential mechanism and its associated driving gear wheel is the same, and a slipping clutch device for transmitting power between one driven element of the differential mechanism to its associated driving gear wheel. 90
5. Mechanism for driving the impeller of a supercharger for an internal combustion engine including in combination coaxial driving and driven shafts, an impeller connected to the driven shaft, at least two lay shafts, gearing connecting each lay shaft to the driving and to the driven shaft; the gearing between the lay shafts and one of such driving and driven shafts including mechanical differential mechanism one element of which is connected to said one of such driving and driven shafts while the other two elements act respectively on the two lay shafts, and a slipping clutch device of the hydraulic reaction type incorporated in at least one of the lay shafts for the purpose set forth. 95
6. Mechanism for driving the impeller of a supercharger for an internal combustion engine including in combination coaxial driving and driven shafts, an impeller connected to the driven shaft, at least two lay shafts, gear wheels on the lay shafts meshing with a gear wheel on one of such coaxial shafts, gearing between the second coaxial shaft and the lay shafts comprising mechanical differential mechanism one element of which is rigidly connected to the said second coaxial shaft while the other two elements are each freely mounted coaxially with the said second coaxial shaft and are connected by gearing respectively to the two lay shafts, and a slipping clutch device incorporated in the transmission mechanism to limit the torque which can be transmitted therethrough. 100
7. Mechanism for driving the impeller of a supercharger for an internal combustion engine including in combination coaxial driving and driven shafts, an impeller connected to the driven shaft, at least two lay shafts, gear wheels on the lay shafts meshing with a gear wheel on one of such coaxial shafts, gearing between the second coaxial shaft and the lay shafts comprising mechanical differential mechanism one element of which is rigidly connected to the said second coaxial shaft while the other two elements are each freely mounted coaxially with the said second coaxial shaft and are connected by gearing respectively to the two lay shafts, and a slipping clutch device of the hydraulic reaction type for transmitting power between driving and driven parts of one of the lay shafts. 105
8. Mechanism for driving the impeller of a supercharger for an internal combustion engine including in combination a main driving shaft, a driven shaft coaxial therewith, an impeller carried by the driven shaft, an intermediate driving shaft arranged parallel to the main driving shaft, gearing connecting the main driving shaft to the intermediate driving shaft, mechanical differential transmission mechanism arranged coaxially with the intermediate driving shaft and comprising a driving element connected to the intermediate driving shaft, and two driven elements arranged coaxially with this intermediate driving shaft, a gear wheel on the driven shaft, driving gear wheels meshing with diametrically opposite parts of the gear wheel on the driven shaft, means for transmitting power from one driven element of the differential mechanism to one of such driving gear wheels and from the other driven element of the differential mechanism to the other driving gear wheel, the arrangement being such that the transmission ratio as between each of the driven elements of the differential mechanism and its associated driving gear wheel is the same, and a slipping clutch device for transmitting power between one driven element of the differential mechanism to its associated driving gear wheel. 110
9. Mechanism for driving the impeller of a supercharger for an internal combustion engine, including in combination a main driving shaft, a driven shaft coaxial therewith, an impeller coupled to the driven shaft, an intermediate driving shaft arranged with its axis parallel to that of the main driving shaft, gearing connecting the intermediate driving shaft to the main driving shaft, mechanical differential mechanism arranged coaxially with the intermediate driving shaft and comprising a driving member connected to the intermediate driving shaft and two driven elements freely rotatable about the axis of the intermediate driving shaft, a gear wheel rigidly connected to one of such driven elements, a gear wheel on the driven shaft with which such driven element gear wheel meshes, a lay shaft, a gear wheel on said lay shaft meshing with the gear wheel on the driven shaft, gearing connecting the other driven element of the differential mechanism to the lay shaft, and a slipping clutch device for transmitting power between the lay shaft and the gear wheel which transmits power to the driven shaft. 115

16. Mechanism for driving the impeller of a supercharger for an internal combustion en- 150

- gine including in combination a main driving shaft, a driven shaft coaxial therewith, an impeller carried by the driven shaft, an intermediate driving shaft arranged parallel to the main driving shaft, gearing connecting the main driving shaft to the intermediate driving shaft, mechanical differential mechanism arranged coaxially with the intermediate driving shaft and comprising a driving element connected to the intermediate driving shaft and two driven elements arranged coaxially with this intermediate driving shaft, a gear wheel on the driven shaft, gear wheels meshing with diametrically opposite parts of the gear wheel on the driven shaft, means for transmitting power from one driven element of the differential mechanism to one of such gear wheels and from the other driven element of the differential mechanism to the other gear wheel, and a slipping clutch device coupling the lay shaft to the gear wheel through which power is transmitted to the driven shaft. 80
11. Mechanism for driving the impeller of a supercharger for an internal combustion engine, including in combination a main driving shaft, a driven shaft coaxial therewith, an impeller coupled to the driven shaft, an intermediate driving shaft arranged with its axis parallel to that of the main driving shaft, gearing connecting the intermediate driving shaft to the main driving shaft, mechanical differential mechanism arranged coaxially with the intermediate driving shaft and comprising a driving member connected to the intermediate driving shaft and two driven elements freely rotatable about the axis of the intermediate driving shaft, a gear wheel rigidly connected to one of such driven elements, a gear wheel on the driven shaft with which such driven element gear wheel meshes, a lay shaft, a gear wheel on said lay shaft meshing with the gear wheel on the driven shaft, gearing connecting the other driven element of the differential mechanism to the lay shaft, and a slipping clutch device coupling the lay shaft to the gear wheel through which power is transmitted to the driven shaft. 95
12. Mechanism for driving the impeller of a supercharger for an internal combustion engine including in combination a driving shaft, a driven shaft, an impeller connected to the driven shaft, at least two lay shafts, gearing connecting each lay shaft to the driving and driven shafts and comprising mechanical differential mechanism having three elements two of which are operatively connected respectively to the two lay shafts while the third element is operatively connected to one of the other shafts, and a slipping clutch device included in the mechanism to prevent the transmission of excessive torque therethrough. 100
13. Mechanism for driving the impeller of a supercharger for an internal combustion engine, including in combination a driving shaft, a driven shaft, an impeller connected to the driven shaft, at least two lay shafts, gearing connecting each lay shaft to the driving and driven shafts, mechanical differential mechanism comprising three elements two of which are operatively connected respectively to the two lay shafts while the third element is operatively connected to the driving shaft, and a slipping clutch device included in the mechanism to prevent the transmission of excessive torque therethrough. 105
14. Mechanism for driving the impeller of a supercharger for an internal combustion engine including in combination a driving shaft, a driv- 110
- en shaft coaxial therewith, an impeller connected to the driven shaft, at least two lay shafts, gearing connecting each lay shaft to the driving and driven shafts, the gearing between the lay shafts and one of such driving and driven shafts including mechanical differential mechanism ensuring equalization of torque through the lay shafts, and a slipping clutch device included in one of said lay shafts to prevent the transmission of excessive torque therethrough. 115
15. Mechanism for driving the impeller of a supercharger for an internal combustion engine including in combination a driving shaft, a driven shaft coaxial therewith, an impeller connected to the driven shaft, at least two lay shafts, gearing connecting each lay shaft to the driving and driven shafts, the gearing between the lay shafts and one of such driving and driven shafts including mechanical differential mechanism ensuring equalization of torque through the lay shafts, and a slipping clutch device of the hydraulic reaction type included in the mechanism to prevent the transmission of excessive torque therethrough. 120
16. Mechanism for driving the impeller of a supercharger for an internal combustion engine from and at a higher speed than a driving shaft, including in combination coaxial driving and driven shafts, an impeller connected to the driven shaft, at least two lay shafts, gear wheels on the lay shafts meshing with diametrically opposite points of a gear wheel on the driven shaft, gearing between the driving shaft and the lay shafts comprising mechanical differential mechanism ensuring equalization of torque through the lay shafts, and a slipping clutch device included in the mechanism to prevent the transmission of excessive torque therethrough. 125
17. Mechanism for driving the impeller of a supercharger for an internal combustion engine from and at a higher speed than a driving shaft, including in combination coaxial driving and driven shafts, an impeller connected to the driven shaft, at least two lay shafts, gear wheels on the lay shafts meshing with diametrically opposite points of a gear wheel on the driven shaft, gearing between the driving shaft and the lay shafts comprising mechanical differential mechanism one element of which is rigidly connected to the said driving shaft while the other two elements are each freely mounted coaxially with the said driving shaft and are connected by gearing respectively to the two lay shafts, and a slipping clutch device incorporated in the mechanism to prevent the transmission of excessive torque therethrough. 130
18. Mechanism for driving the impeller of a supercharger for an internal combustion engine from and at a higher speed than a driving shaft, including in combination coaxial driving and driven shafts, an impeller connected to the driven shaft, at least two lay shafts, gear wheels on the lay shafts meshing with diametrically opposite points of a gear wheel on the driven shaft, gearing between the driving shaft and the lay shafts comprising mechanical differential mechanism of a type in which the relative rotation between the element is not limited, one element of which is rigidly connected to the said driving shaft while the other two elements are each freely mounted coaxially with the said driving shaft and are connected by gearing respectively to the two lay shafts, and a slipping clutch device included in one of said lay shafts to prevent the transmission of excessive torque therethrough. 135
- 75

clutch device included in at least one of the lay shafts to prevent the transmission of excessive torque therethrough.

19. Mechanism for driving the impeller of a supercharger for an internal combustion engine from and at a higher speed than a driving shaft, including in combination coaxial driving and driven shafts, an impeller connected to the driven shaft, at least two lay shafts, gear wheels on the lay shafts meshing with diametrically opposite points of a gear wheel on the driven shaft, gearing between the driving shaft and the lay shafts comprising mechanical differential mechanism of a type in which the relative rotation between the elements is not limited, one element of which is rigidly connected to the said driving shaft while the other two elements are each freely mounted coaxially with the said driving shaft and are connected by gearing respectively to the two lay shafts, and a slipping clutch device of the hydraulic reaction type included in one of the lay shafts to prevent the transmission of excessive torque therethrough.
